PRINTING MECHANISM

Robert O. Buehler, Chicago, Ill., assignor to
 Victor Adding Machine Co., Chicago, Ill., a corporation of Illinois

Application September 13, 1941, Serial No. 410,691

5 Claims. (Cl. 101—96)

My invention relates generally to printing mechanisms, and more particularly to improvements in means for printing identifying words in association with amount designations on the record strips of adding and calculating machines.

It is an object of my invention to provide an improved mechanism forming part of an adding or calculating machine whereby amount characterizing or classifying indicia may be selectively imprinted upon the record tape.

A further object is to provide an improved word printing mechanism for adding machines and the like wherein the words to be printed may be changed at will and any one of a plurality of selected words may be instantaneously conditioned for printing by a simple act of the operator.

A further object is to provide an improved word printing mechanism for adding machines and the like capable of printing simultaneously with the amount a plurality of identifying indicia, a plurality of combinations of which may be preset and thereafter individually used at will.

A further object is to provide an improved identifying word printing mechanism for adding machines and the like capable of printing any one of a group of words by the depression of a single key, and in which the words of the group may be changed at will.

A further object is to provide an improved printing mechanism for adding machines and the like which is very flexible in operation, may be economically manufactured, and which may be incorporated in a conventional adding or calculating machine without appreciably altering the construction of the latter.

Other objects will appear from the following description, reference being had to the accompanying drawings, in which:

Fig. 1 is a plan view of an adding machine incorporating the invention;

Fig. 2 is a longitudinal sectional view taken generally on the lines 2—2 of Figs. 1 and 3;

Fig. 3 is a generally transverse sectional view drawn to an enlarged scale, and taken substantially on the line 3—3 of Fig. 2, some of the parts being omitted and others shown in section, more clearly to illustrate the operative parts of the mechanism;

Fig. 4 is a fragmentary sectional view showing the details of the keys and word setting wheels;

Fig. 5 is a side elevational view of one of the type wheels;

Fig. 6 is a similar view of one of the setting wheels;

Fig. 7 is a fragmentary plan view of an adding machine incorporating a modified form of the invention; and

Figs. 8 and 9 are sectional views taken on the lines 8—8 and 9—9 of Fig. 7.

In the use of adding and similar machines, it is frequently desirable to have the tally or paper record strip thereof provide some identifying legend to indicate the character of the 10 transactions represented by the amounts printed thereon. For example, adding machines are frequently used in conjunction with a cash drawer as a cash register, and especially under these circumstances it is useful for the proprietor to 15 be able to ascertain from the tally strip the classes of goods represented by the sales or credit amounts printed on the strip. At the end of the day, the tally record may then be used for various recapitulation and bookkeeping purposes.

20 In other uses of adding machines, it is likewise frequently desirable, whenever the record strip is retained for checking or record purposes, to be able to determine from the strip itself the type of transaction represented by each of the 25 amounts printed on the record strip.

It has been proposed in the past to accomplish this purpose by providing an additional type wheel bearing logotypes to imprint the desired identifying word adjacent the amounts on the 30 record strip and to provide keys or other means for selecting the word to be printed. Due to the frequently changing uses to which an adding machine may be put, and due to the changing character of the transactions in a given business, such 35 mechanisms did not prove satisfactory since it was obviously inconvenient to obtain a new type wheel every time it was desired to change one or more of the logotype appearing thereon. By the use of the present invention, such difficulty is obviated since the user of the machine may readily change the identifying words to be printed and may set up the machine so as to imprint any one of a plurality of words simply by the depression of a single key.

40 As shown in Fig. 1, the invention is incorporated in an adding machine comprising a case 10 having an amount keyboard 12, an operating handle 14, a platen 16 with the usual paper feed mechanism and inking ribbon for making printing impressions upon a record strip 18. The machine may be equipped with any suitable operation controls, such as indicated at 19 and 20. The adding machine may, of course, be of any suitable construction capable of imprinting the 45 amounts added or subtracted and positive or neg-

ative totals, together with such identifying characters as "*", "T," "ST," "NP," "CR," etc., as is common in the art.

In addition to the numeral keys and any other control keys which may be provided, the keyboard includes a plurality of keys 22 located adjacent sight openings or windows 24 formed in the keyboard plate 26.

As best shown in Fig. 2, the printing mechanism is illustrated as comprising type wheels 28, each rotatably mounted upon a stud 30 carried by an arm. As indicated in Fig. 5, each of the type wheels has type to print twenty-three letters of the alphabet and in addition has a blank space. The type for the letters "O" and "Q," "U" and "V," and "X" and "Z" are respectively combined into composite characters, readable as either of the two characters, so as to reduce the sizes of the type wheels and other parts.

Each of the studs 30 is secured to an arm 32 which is pivoted upon a cross rod 34 suitably supported in the main frame plates of the machine. Each of the type wheels 28 has a pinion 36 rigidly secured to or formed integrally therewith, this pinion meshing with an idler pinion 38 rotatably mounted upon its stud 39 secured to its associated arm 32. An alignment pawl 40 is provided for each of the type wheels, being pivoted on the cross rod 34. Each of the pawls 40 is urged to swing counter-clockwise with respect to its associated arm 32 by a spring 42 tensioned between ears 43 and 44 formed on the arm 32 and pawl 40, respectively. Such counter-clockwise movement of the retaining pawl with respect to its arm is prevented by a stop 46 when the parts are in the normal position shown in Fig. 2, so that when in this position, the idler pinion 38 is free to be rotated.

The idler pinion 38 is adapted to mesh with a segmental gear 48 mounted for rotation upon a fixed shaft 50. Each of the segmental gears 48 has a segmental pinion 52 rigidly secured thereto, the latter meshing with a rack 54 formed upon an actuator 56. The actuator 56 is mounted for reciprocation upon a pair of fixed rods 58, 59, which extend through suitable slots 60 formed in the actuator, the actuators being suitably spaced by a comb 62 and urged to move rearwardly by tension springs 64, each of which has one end suitably secured to the comb 62 and its other end secured to one of the actuators. A restoring bail bar 66 extends through slots 68 formed in the actuators 56, and is reciprocated rearwardly and again forwardly at appropriate times in the operating cycle of the machine to permit the actuators 56 to travel rearwardly, thereby to set the type wheels 28, and upon completion of the printing operation to restore the actuators to normal position. An aligner bar 70 is brought into engagement with the teeth of the segmental gears 48 after the actuators have completed their rearward motion so as to align the segments and thereby align the type wheels 28. In the course of the printing operation, a restoring bail 72 is moved rearwardly and thereafter suitable latching means (not shown) are tripped to permit tension springs 74 to swing their respective type carrying arms 32 clockwise, to cause the type thereof to strike the ribbon 76 and make a printing impression upon the record strip 18.

The printing mechanism, as thus far described, is similar in construction and operation to that disclosed in greater detail and claimed in the co-pending application of Thomas O. Mehan, Serial No. 372,290, filed December 30, 1940.

From the foregoing, it will appear that in order to obtain an impression of any desired word upon the record strip 18, it is necessary that the rearward travel of actuators 56 be differentially limited to bring the desired type in printing alignment. This means comprises a plurality of setting wheels 80, illustrated as comprising nine groups of six wheels each. Each group of setting wheels is mounted for rotation upon a shaft 82 projecting laterally from and rigidly secured to a key stem 84. The key stems 84 are suitably mounted for vertical reciprocation in a pair of keyboard frame plates 86 and 88 and have the key buttons 22 secured at their upper ends.

Each of the key stems is provided with a camming surface 90, adapted to engage sidewardly projecting lugs formed on a locking slide 92 which is urged to its rearward position by a tension spring 94 and is adapted to latch over a shoulder 96 formed on each of the key stems directly above its camming surface 90. Each of the keys 22 has a return spring 97. The arrangement is such that a depressed key will be held in depressed position until another key is depressed or partially depressed. In addition to moving the latching slide 92 forwardly, the camming surface 90 of a depressed key also cams a disengaging slide 99 forwardly and holds it in such forward position. The forward extremity of the disengaging slide 99 engages an arm 100 of a bail 100 suitably pivoted at 102 and urged to swing clockwise by a tension spring 104. The cross bar 106 of the bail 100 normally arrests the rearward movement of the actuators 56 by engaging with hooks 108 formed at the forward ends of the actuators.

Each of the setting wheels 80 is rigidly secured to the sidewardly extending hub portion of a gear 110 rotatable on one of the shafts 82, the setting wheels 80 being held by spring detents 112 in any position to which they may be adjusted. The detents 112 may be secured to the keyboard plate 26 and have suitably formed portions engageable with the teeth of the gears 110. The spring detents 112 are sufficiently elastic that upon downward movement of the setting wheels, they will follow the gears 110 thereof until the latter mesh with gears 114 which are rotatably mounted upon fixed shafts 116. Each of the gears 114 has a pinion 118 rigidly secured thereto, these pinions being permanently in mesh with racks 120 formed upon the actuators 56.

Upon depression of a key stem, its gears 110 engage their cooperating gears 114, the key stem being latched in depressed position by the latching slide 92, with the gears 110 and 114 in engagement. Depression of the key also swings the cross bar 106 of bail 100 from in front of the hooks 108 of the actuators 56, so that the latter are free to move rearwardly when the restoring bail bar 66 is moved rearwardly during the course of the operating cycle of the machine.

Each of the setting wheels 80 is provided with a stop lug 121, which is adapted to cooperate with a stop pin or key 122 fixed on its shaft 82.

As indicated in Fig. 6, each of the setting wheels 80 has twenty-three letters of the alphabet marked upon its cylindrical surface to correspond with the type faces on type wheels 28, the letters being separated by grooves or notches 124 adapted to be engaged by a stylus inserted through the adjacent window or sight opening 24. Thus, by means of such stylus, the setting wheels 80 may be moved counter-clockwise from their normal positions shown to bring any de-

sired letter beneath the sight opening. Any six-letter word or abbreviation may be set up on the setting wheels 80 and the operator of the machine will have available nine six-letter words or abbreviations which may be printed adjacent the amount impression merely by depressing the appropriate key 22 at the time the amount keys are depressed. Any suitable means may be provided to move the latching slide 92 forwardly shortly before the completion of the operating cycle of the machine to permit the restoration to normal position of any depressed key under the influence of its restoring spring 91. Also, means may be provided to lock the latching slide 92 against forward movement throughout the operating cycle of the machine to prevent inadvertent depression of the keys 22 during this period.

In using the machine, the operator will first pre-set the setting wheels 80 to indicate the different words which he expects to have occasion to use, setting these members to indicate such words, as "Dress," "Suit," "Shoes," etc., as indicated in Fig. 1.

Thereafter, assuming the machine is being used in the manner of a cash register to record sales, and assuming that the operator has sold a dress for \$12.50, the operator will depress the key 22 associated with a group of setting wheels 80 which have been adjusted to register "Dress," and after depressing the appropriate amount keys of the keyboard 12, will operate the handle 14, or operate the motor control key, if the machine is electrically driven. Upon depression of one of the keys 22, the latching plate 92 will be operated to latch the key in depressed position, and the slide 99 will be moved forwardly by the camming surface 90 of the depressed key stem 84 to cause the cross bar of the bail 106 to drop from behind the hooks 108, thereby freeing the actuators 56 for rearward movement.

During the course of the operating cycle of the machine, as the restoring bail bar 66 is moved rearwardly, the tension springs 64 will slide the four left-most actuators 56 rearwardly. Since the depression of the key causes the gears 110 associated therewith to mesh with the cooperating gears 114, it will be apparent that a positive driving connection between the setting wheels 80 and type wheels 28 will have been established. Therefore, the rearward movement of each of the actuators 56 will continue until the setting wheel 80 associated therewith has been returned clockwise to its normal position, when the movement is limited by engagement of its stop lug 120 with the stop key 122. Such clockwise movement of the setting wheel results in corresponding counter-clockwise angular movement of associated type wheel 28. Since the arrangement of the type characters on the type wheels 28 corresponds with the arrangement of the letters marked upon the setting wheels 80 (see Figs. 5 and 6), the type characters corresponding to the letters initially set up in the associated setting wheels 80 will be brought into printing position, and upon release of the type arms will strike the record strip 18 through the ribbon 76 to print the word "Dress" on the strip.

During the swinging movement of the type wheels 28 (from their normal position in which they are shown in the drawings) to printing position, the aligning pawls 40 will engage in the spaces between the teeth of the idler pinions 38 and thereby prevent the latter, and hence the type wheels, from rotating. The aligner pawls 40

will also prevent rotation of the type wheels during the return stroke of the type wheel carrying arms 32 so that the idler pinions 38 will engage the segmental gears 48 in proper mesh.

- 5 Upon completion of the printing operation, the actuators 56 will be drawn forwardly by the restoring bail bar 66 and will be latched in forward position by the engagement of their hooks 108 over the cross bar 106 of the bail 100. Such 10 restoration of the actuators 56 will also result in restoring the setting wheels 80 to the positions in which they were originally set, namely, to indicate the word "Dress." After the setting wheels have been thus restored, the latching slide 15 92 will be moved forwardly, in the customary manner, to release the depressed key, and the latter will move upwardly, the setting of its wheels 80 being maintained by the spring detents 112.
- 20 From the foregoing, it will appear that the operator may set the mechanism so as to make it capable of printing any one of nine pre-selected words or abbreviations of six letters or less merely by the depression of one of the keys 22, and that 25 the words or abbreviations may be changed at will very quickly and easily. The machine is thus very flexible in the sense that it may readily be adjusted for printing the words characteristic of particular kinds of businesses. The invention is 30 very useful from the point of view of the manufacturer and salesman as well as the user, since it is unnecessary to make up specifically a type-wheel containing the logotypes required for a particular business, but instead, the manufacturer or salesman may readily set the machine for the printing of the words selected by the customer.

- In Figs. 7, 8, and 9 is disclosed a modification of the invention in which the setting of the type is controlled by notched plate keys. The type wheels and associated parts may be of the same construction as illustrated in Figs. 1 to 6, and the same reference characters have been applied to such of the parts as correspond with those 40 previously described. The type wheels are set by differentially movable actuators 130, each of which has at its forward end a series of twenty-four stepped stop faces 132 which are adapted, 45 upon rearward movement of the actuators 130 under the influence of their springs 64, to engage a notched key plate 134. The notched key plate is firmly held in a suitable guide 136 which is secured in keyboard frame plates 138, which may 50 likewise be used as supports and guides for the numeral keys. Each of the notched key plates 134 has a forwardly extending flange 140 which limits the extent of insertion of the key in the guide 136 and on its outer surface bears a legend such as the word "Dress" appearing in Fig. 7. 55 The key plate 134 has its notches cut out in such manner that upon the rearward movement of the actuators 130, they will be arrested in position to cause the faces of the type wheels 28 to be in position for printing the word "Dress."
- If a notch in the key plate 134 is so deep (as the notch in line with the right-most actuator 130 is shown in Fig. 9), the actuator will not be arrested by the key plate, but will continue its 60 rearward movement through a complete stroke by the restoring bail bar 66 and bring the blank space of the type wheel 28 in the printing line. Thus, if, through inadvertence or by intent, no notched plate key 134 is inserted in the guide 136, all of the actuators 130 will move rearwardly 65 70 75

through their full strokes, and no legend will be printed upon the record strip.

The notched plate keys may be easily inserted and removed from the guide 136, and for the sake of convenience, are preferably kept in a magazine 144 which may be secured to the adding machine casing and which is provided with a plurality of slots 146 in its top. Thus, upon removal of a given key 134 from its effective position in the guide 136, it may be placed in the convenient rack 144 and replaced by another key.

Thus, in using the machine of Figs. 7, 8, and 9, the operator need merely insert the proper key plate 134 in the guide 136, depress the appropriate amount keys, and operate the machine, whereupon, a legend corresponding to the key plate selected will be printed adjacent the amount, all of the purposes heretofore described. If the same legend is to be repeated, the operator merely presses the required amount keys, since the identifying legend or word will be repeatedly printed adjacent the amounts upon successive operations of the machine, until the controlling notched key plate 134 is removed.

While I have shown and described particular embodiments of my invention, it will be apparent to those skilled in the art that numerous modifications and variations may be made without departing from the more fundamental principles of the invention. I therefore desire, by the following claims, to include within the scope of my invention, all such variations and modifications by the use of which substantially the results of my invention may be obtained by the use of the same or equivalent means.

I claim:

1. In a word printing mechanism for adding machines, the combination of a key, a shaft movable by said key, a plurality of manually set wheels rotatable on said shaft, stop means to limit rotational movement of said wheels, resilient detents to hold said wheels in set position, a plurality of type position controlling actuators, and means providing a driving connection between said wheels and actuators upon operation of said key.

2. In a machine for printing words, a plurality of word selecting keys, a plurality of differentially settable stop devices for each of said keys, each of said stop devices comprising a gear and wheel having alphabetical indicia thereon, a machine casing having openings adjacent said wheels to permit adjustment of the stop position thereof, a detent for each of said wheels to hold it in adjusted position, a plurality of differentially movable type carriers each carrying type representing substantially all of the letters of the alphabet, and each associated respectively with one of said stop devices of each of said keys, and means operable upon depression of one of said

keys to render its stop devices effective to control the differential movement of said type carriers.

3. In a machine for printing words, a plurality of word selecting keys, a plurality of differentially settable stop devices for each of said keys, each of said stop devices comprising a gear and wheel having alphabetical indicia thereon, a machine casing having openings adjacent said wheels to permit adjustment of the stop position thereof, a plurality of differentially movable type carriers each carrying type representing substantially all of the letters of the alphabet, and each associated respectively with one of said stop devices of each of said keys, and means operable upon depression of one of said keys to render its stop devices effective to control the differential movement of said type carriers.

4. In a word printing mechanism, a plurality of differentially movable type carriers having type for printing substantially all of the letters of the alphabet, an actuator for each of said type carriers, each actuator having a rack portion, a plurality of groups of rotatable setting wheels each having a stop to limit its rotary movement to a stop position, a machine casing having openings adjacent said wheels whereby said wheels may be manually preset selected angular distances from their stop positions, gearing capable of forming driving connections between said rack portions and said wheels respectively, keys individually operable to cause said gearing to connect a selected group of said wheels with said actuator rack portions, and yielding means for operating said actuators under the control of the selected group of said wheels thereby to return said wheels to their stop positions and thus move said type carriers to positions corresponding to the angular distances to which the wheels of said group were manually preset.

5. In a printing machine, the combination of a plurality of type carriers having type faces capable of printing substantially all of the letters of the alphabet, differentially movable actuators for positioning said type carriers to imprint words, means to control the differential movement of said actuators, said last named means comprising a plurality of selectively operable keys, a plurality of setting wheels associated with each of said keys, stops to limit movement of said setting wheels, detent means to hold said wheels in set position, a casing having openings exposing said wheels for manual setting in preselected positions relative to their limit stops, means operable upon depression of each of said keys to provide an operative connection between its associated setting wheels and said actuators, and yielding means to move said actuators in a direction to cause said setting wheels to be rotated toward their limit stop positions, whereby said setting wheels may limit the movement of said actuators and thereby control the positions of said type carriers.

ROBERT O. BUEHLER.
